CLAIM

The ornamental design for an upright multi-surface vacuum cleaner, as shown and described.

DESCRIPTION

FIG. 1 is a front perspective view of an upright multi-surface vacuum cleaner showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof; and,

(Continued)

FIG. 7 is an enlarged top view of the upright multi-surface vacuum cleaner.

The details of the upright multi-surface vacuum cleaner shown in broken lines form no part of the claimed design.

1 Claim, 7 Drawing Sheets
